UNITED STATES PATENT OFFICE.

CARL P. BROCKWAY, OF TOLEDO, OHIO, ASSIGNOR TO INDUSTRIAL RESEARCH CORPORATION, OF TOLEDO, OHIO, A CORPORATION OF DELAWARE.

OIL-CIRCULATING SYSTEM.

Application filed October 22, 1920, Serial No. 418,804. Renewed April 23, 1924.

To all whom it may concern:

Be it known that I, CARL P. BROCKWAY, a citizen of the United States, residing at Toledo, in the county of Lucas and State 5 of Ohio, have invented certain new and useful Improvements in Oil-Circulating Systems, of which I declare the following to be a full, clear, and exact description.

This invention relates to a system for 10 automatically circulating oil to the parts of an internal combustion engine requiring lubrication.

One object of the invention is to provide a simple, inexpensive, and positive 15 means of propelling oil from the reservoir in the base of the crank case to the portions of the engine needing lubrication.

My invention is an improvement over old 20 methods of circulating oil by splashing, in that the oil is given a positive thrust by a paddle in a restricted passage whereby the oil is conveyed to an auxiliary trough from which a splashing member attached to the piston rod propels the oil to the desired 25 portions of the engine.

Another object of the invention is to furnish means for efficiently lubricating the engine with a limited amount of oil in the 30 crank case, and to at all times maintain a thorough circulation of oil through the crank case, thus keeping the oil homogeneous, and cool. Other objects and advantages relating to details of construction and economies of manufacture will appear as 35 I proceed with the description of that embodiment of the invention, which for the purposes of the present application I have illustrated in the accompanying drawings.

Figure I is a vertical sectional view of 40 one form of my invention.

Figure II is a vertical sectional view at right angles to Figure I, and taken along the line II-II of Figure I, looking in the direction indicated by arrows.

45 In Figure I, the casing 1 houses the crank 2 journaled in the casing. Upon crank 2 is supported the piston rod 3, having the paddle 4 extending from one end and reaching through the slotted partition or trough 5 which has the sections 6, 6 for retaining 50 oil serving as an auxiliary reservoir above the main reservoir 7 in the base of the casing. Between the paddle 4, and the crank 2, is the multiple prong splasher 8, dipping into the oil in the trough 5, for

splashing the oil into the upper portion of the casing for lubricating the piston and the various bearings. At the bottom of the trough 5 is provided the annular channel 9 having a slot 10 connecting it with the upper side of the trough, and having the passageways 11 communicating with the reservoir 7 in which the channel is partly submerged. In the sides of the trough 5 are arranged the passageways 12 for draining excess accumulation of oil.

The operation is as follows: The crank 2 on rotating directs the lower end of the piston rod together with the paddle 4 in a circular path so that the paddle assumes the position shown in dotted lines in Figure I, beginning at the right hand side of the figure in the position shown, dipping down into the channel 9 as the cycle progresses drawing in oil through the perforations 11, and impelling oil toward the left hand end of the channel where it spills over the edge of the channel and into the trough 5 where the diverging walls of the trough cause the oil to accumulate in the path of the prongs 8 so that the oil thus accumulated is plashed in the subsequent cycle.

The passageways, or perforations 12 allow the oil to drain to a fixed level thus preventing an excessive accumulation of oil in 85 the trough 5, as well as providing a means for continually circulating the oil, since the oil returning from the splashing of the bearings passes largely down the inside walls of the casing 1, then down from the 90 edges of the trough 5, and through the perforations 12, while fresh oil from the reservoir is pumped into the trough by the paddle 4.

In the above manner the oil is given a 95 continuous circulation, whereby the entire quantity of oil in the reservoir is utilized, and pockets of stagnated oil are avoided. The active circulation of the oil from the reservoir 7, through opening 11, channel 9, 100 trough sections 6, 6; upper parts of casing 1, down the inside walls of the casing, then down the upper walls of the trough 5, and through the perforations 12, back to the reservoir 7, maintains the oil at a 105 uniform moderate temperature by virtue of the cooling derived from the walls of the casing.

I am aware that the particular embodiment of my invention above described and

illustrated in the accompanying drawing is susceptible of considerable variation without departing from the spirit thereof and therefore I desire to claim my invention broadly as well as specifically as indicated by the appended claims.

I claim as my invention:

1. In a lubricating system for an internal combustion engine, a casing, a crank journaled therein, carrying a piston rod, a main reservoir, and an auxiliary reservoir above said main reservoir, means attached to said piston rod for lifting oil from said main reservoir into said auxiliary reservoir and simultaneously splashing oil from said auxiliary reservoir for lubricating the engine.

2. In a lubricating system for an internal combustion engine, a casing, a crank journaled therein, a piston rod supported on said crank, a slotted trough having a section to retain oil, an extension on said piston rod including a paddle reaching through said slot for lifting oil to fill said trough, and a splasher for throwing oil from said trough for lubricating said engine.

3. In a lubricating system for an internal combustion engine, a casing, a crank journaled therein, a piston rod supported on said crank, a slotted trough having a section to retain oil, an extension on said piston rod including a paddle reaching through said slot for lifting oil to fill said trough, and a multiple prong splasher for throwing oil from said trough for lubricating the engine.

4. In a lubricating system for an internal combustion engine, a casing, a crank journaled therein, a piston rod supported on said crank, a slotted trough having a section to retain oil, an extension on said piston rod including a paddle reaching through said slot for lifting oil to fill said trough, and a splasher for throwing oil from said trough for lubricating said engine, said trough having overflow means for draining excess accumulation of oil.

5. In an internal combustion engine, lubricating means including a casing having a reservoir in its base, a crank journaled in said casing, a piston rod supported upon said crank having a paddle extending therefrom, a slotted trough supported in said casing above said reservoir, said paddle travelling through said slot for propelling oil from said reservoir into said trough, and additional means extending from said rod for splashing the oil deposited in said trough, whereby the splashed oil is circulated to the portions of the engine to be lubricated.

6. In a lubricating system for an internal combustion engine, a casing, a crank journaled therein, a piston rod mounted on said crank having oil propelling means at one end, a reservoir in the base of said casing, an annular channel partly submerged in said reservoir having a slot in one of its walls, and passageways in certain of its walls communicating with said reservoir, an auxiliary container above said reservoir between the ends of said channel, said container having upwardly diverging walls with overflow passageways for draining excess accumulation of oil from said container, said propelling means elevating oil from said reservoir to said container, and auxiliary means mounted on said piston rod above said propelling means for splashing oil from said container to lubricate the engine.

7. In a lubricating system for an internal combustion engine, a casing, a crank journaled therein, a piston rod mounted on said crank having oil propelling means at one end, a reservoir in the base of said casing, an annular channel partly submerged in said reservoir having a slot in one of its walls and passageways in certain of its walls communicating with said reservoir, a trough above said reservoir between the ends of said channel, said propelling means elevating oil from said reservoir to said trough, and auxiliary means mounted on said piston rod above said propelling means for splashing oil from said trough to lubricate the engine.

8. In a lubricating system for an internal combustion engine, a casing, a crank journaled in said casing carrying a piston rod thereon, a reservoir in the base of said casing, a partition separating the reservoir from the upper part of said casing, said rod having an extension comprising a paddle extending through said partition during a portion of the cycle for raising oil from said reservoir to the upper side of said partition, and a splashing member mounted on said rod adjacent said paddle for propelling oil to the portions of the engine to be lubricated.

9. In a lubricating system for an internal combustion engine, a casing, a crank journaled therein, carrying a piston rod, a main reservoir, and an auxiliary reservoir above said main reservoir, means for lifting oil in said casing, and means for splashing said lifted oil, said lifting and splashing means being secured to the piston.

In testimony whereof, I affix my signature.

CARL P. BROCKWAY.
